UNITED STATES PATENT OFFICE.

JAMES M. MIDDLEBROOKS, OF BIRMINGHAM, ALABAMA.

ACTUATOR FOR TRAFFIC-SIGNALS.

1,339,660.

Specification of Letters Patent. Patented May 11, 1920.

Original application filed October 1, 1918, Serial No. 256,409. Divided and this application filed February 21, 1919. Serial No. 278,462.

To all whom it may concern:

Be it known that I, JAMES M. MIDDLEBROOKS, a citizen of the United States, residing at Birmingham, in the county of Jefferson and State of Alabama, have invented 5 certain new and useful Improvements in Actuators for Traffic-Signals, of which the following is a specification.

This invention relates to an improved 10 actuator for motor vehicle traffic signals, being a division of my pending application for traffic signal, filed October 1, 1918, Serial No. 256,409.

The invention has as its primary object 15 to provide an actuator which may be operated with ease for controlling a signaling device connected therewith to selectively display a number of different signals.

The invention has as a further object to 20 provide an actuator employing a vertically movable actuating sleeve for operating the signal and wherein said sleeve will be equipped with means for automatically locking the sleeve in vertically adjusted position.

And the invention has as a still further 25 object to provide an actuator which may, without difficulty, be readily connected with substantially any conventional type of motor vehicle.

Other and incidental objects will appear 30 hereinafter. In the drawings:

Figure 1 is a vertical sectional view of 35 my improved actuator;

Fig. 2 is a perspective view of the signal 40 for which the present actuator is particularly designed, this signal forming the subject matter of my pending application referred to;

Fig. 3 is a transverse sectional view taken 45 on the line 3—3 of Fig. 1 and looking in the direction of the arrows;

Fig. 4 is a similar view taken on the 50 line 4—4 of Fig. 1 and looking in the direction of the arrows, and

Fig. 5 is a fragmentary elevation showing 55 one of the catch receiving notches in the standard of the actuator.

In carrying the invention into effect, I 60 employ an upstanding tubular post or standard 10 designed to be mounted adjacent the forward end of a vehicle near the driver's seat. In Fig. 1, the forward portion of the vehicle floor is indicated at 11. The post is 65 inclined rearwardly of the vehicle toward

the driver's seat and, at its lower end is threaded through a floor plate 12 disposed beneath the floor 11. Loosely fitted over the post and resting against the upper face of the floor is a similar plate 13 and connecting 60 these plates are bolts or other suitable fastening devices 14 extending through the floor. The post will thus be rigidly secured in upstanding position. Formed integral with the plate 12 or otherwise mounted adjacent the plate is a bracket 15 carrying a pulley 16 over which a cable 17 is trained. The cable is designed to extend from a signaling device at the rear of a vehicle or otherwise located thereon and for convenience I have, in Fig. 2, shown a signaling 70 device at 18, this signal forming the subject matter of my pending application referred to. The present actuator is particularly designed for use in connection with this signaling device. However, the actuator may, of course, be employed for operating other signals for which it may be adapted.

Slidably fitting over the post 10 is a sleeve 19 upon the upper end of which is threaded 80 a cap 20. Fixed to this cap axially thereof is a handle 21 so that the handle may be turned for rotating the sleeve and, as will now be observed, the forward end portion of the cable 17 is led from the pulley 16 85 through the post 10 and is connected at its adjacent end to the handle. Formed in the post, at suitably vertically spaced points thereon are substantially triangular shaped notches 22 and 23 respectively. Spaced 90 above the notch 23 and in vertical alinement therewith is a slot 24. At the lower edges of the notches 22 and 23 are defined shoulders or ledges 25 and the side walls of these notches converge upwardly from said ledges 95 to provide upwardly inclined beveled shoulders 26 merging into the peripheral face of the post. Riveted or otherwise connected at one end to the sleeve 19 is a spring catch 27 bent, adjacent its free end at substantially 100 right angles to be freely received through a slot in the sleeve. The free end of the catch will thus bear against the peripheral face of the post to ride thereover as the sleeve is shifted vertically upon the post.

As will now be clear, when the handle 21 of the sleeve 19 is grasped and the sleeve lifted upon the post 10, a corresponding pull will be communicated to the cable for operating the signal 18. In this connection, it 110

may be briefly stated that the signal 18 includes a rotatable spring returned character drum to which the cable 17 is operatively connected and which carries a plurality of signals comprising successively the words Watch, Stop, Left, Right, the signal Watch being normally displayed opposite the display opening in the casing and the remaining signals being adapted to be selectively brought opposite said opening into position for display. Consequently, by lifting the sleeve 19 to engage the catch 27 with the ledge 25 of the notch 22, the character drum of the signal will be rotated to display the signal Stop opposite the display opening in the casing. As particularly brought out in Fig. 4 of the drawings, the free end of the catch when engaged with the ledge of the notch 22, will abut the inclined shoulders 26 of said notch. Therefore, continued upward lifting of the sleeve by the handle 21 will serve to ride the catch over said shoulders onto the peripheral face of the post 10 so that the sleeve may be elevated to engage the catch with the ledge of the notch 23. The character drum of the signal will then be rotated to display the signal Left opposite the display opening of the signal casing. Continued upward lifting of the sleeve will then serve to ride the catch over the shoulders 26 of the notch 23 so that the sleeve may be elevated to engage the catch within the slot 24 of the post, when the character drum of the signal will be rotated to display the signal Right opposite the display opening of the signal casing. The sleeve may thus be readily actuated from the driver's seat to operate the signal for giving a signal of an intention of the driver to stop or to turn either to the left or right. The slot 24 is provided so that the catch 27 may engage therein for limiting the sleeve in its upward movement upon the post. However, the end walls of this slot are beveled like shoulders 26 of the notches 22 and 23 and the free end of the catch when engaged within the slot will abut these end walls. Consequently, by slightly rotating the sleeve in either one direction or the other the catch will ride over a corresponding end wall of the slot onto the peripheral face of the post when the sleeve may be lowered to its normal position abutting at its lower end with the upper floor plate 13 of the post. Since the character drum of the signal 18 is spring returned, the drum will, when the sleeve is thus lowered, be counter-rotated to its normal position displaying the pilot signal Watch opposite the display opening of the signal casing. This pilot signal is employed in order that attention may be directed to the signaling device. Should the catch 27 be engaged in either of the notches 22 or 23, the sleeve 19 may be slightly rotated in either direction.

to ride the free end of the catch over a corresponding one of the shoulders 26 onto the peripheral face of the post for permitting the lowering of the sleeve. Thus, it will be seen that the sleeve may be readily actuated for rotating the character drum of the signal 18 to give any desired signal and may then be released and lowered to permit the counter-rotation of the drum to its normal position. I accordingly provide a particularly efficient type of actuator while, at the same time, the device is characterized by extreme simplicity and may, as will be appreciated in view of the preceding description, be readily connected without difficulty to substantially any conventional type of motor vehicle. 70 75 80

Having thus described the invention, what is claimed as new is:

1. An actuator of the character described including a post, vertically spaced ledges formed thereon, a sleeve slidably adjustable vertically upon the post, a flexible actuating element connected with said sleeve, and means carried by the sleeve and adapted to selectively coöperate with said ledges for supporting the sleeve in vertically adjusted position upon the post. 85 90

2. An actuator of the character described including a post, vertically spaced ledges formed thereon, a sleeve slidably adjustable vertically upon the post, a flexible actuating element connected with said sleeve, and means carried by the sleeve and adapted to selectively coöperate with said ledges for supporting the sleeve in vertically adjusted position upon the post, the sleeve being rotatable for disengaging said means from any one of said ledges whereby the sleeve may be lowered to normal position upon 105 the post. 95 100

3. An actuator of the character described including a post, a ledge formed thereon, a shoulder inclining from the ledge to the periphery of the post, a sleeve slidably adjustable vertically upon the post, a flexible actuating element connected with said sleeve, and means carried by the sleeve and engageable with said ledge for locking the sleeve in vertically adjusted position upon 110 the post, said means being adapted to ride over said shoulder whereby the sleeve may be raised upon the post. 115

4. An actuator of the character described including a post, a ledge carried thereby, beveled shoulders at opposite ends of said ledge leading to the periphery of the post, a sleeve slidably adjustable vertically upon the post, a flexible actuating element connected with said sleeve, and means carried by the sleeve and engageable with said ledge for locking the sleeve in vertically adjusted position upon the post, said means being adapted to ride over either of said shoulders whereby the sleeve may be ro- 120 125 130

tated to disengage said means from the ledge to permit the lowering of the sleeve.
5. An actuator of the character described including a post provided with a notch therein defining a ledge having shoulders inclining from the ends thereof to the periphery of the post and beveled to present flat faces leading to the periphery of the post at the ends of the ledge, a sleeve slidably adjustable vertically upon the post, a flexible actuating element connected with said sleeve, and means carried by the sleeve and engageable with said ledge for locking the sleeve in vertically adjusted position upon 10 the post, said means being adapted to ride upwardly over said shoulders onto the periphery of the post whereby the sleeve may

be raised and being adapted to ride transversely over the flat face of either of said shoulders onto the periphery of the post 20 whereby the sleeve may be rotated to disengage the means from the ledge and permit the lowering of the sleeve.

6. An actuator of the character described including a post, a sleeve adjustable thereon, and coacting means carried by the post and sleeve respectively for locking the sleeve in adjusted position upon the post, the sleeve being rotatable for freeing said means. 25

In testimony whereof I affix my signature.

JAMES M. MIDDLEBROOKS. [L. S.] 30
